W. J. EDNEY

TURBINE

Filed Sept. 1, 1922

Fig. 5. 27

Inventor
William J. Edney

Atturston, Haugh & Co

Attorney

UNITED STATES PATENT OFFICE.

WILLIAM JOHN EDNEY, OF SUTTON, ENGLAND.

TURBINE.

Application filed September 1, 1922. Serial No. 585,781.

To all whom it may concern:

Be it known that I, WILLIAM JOHN EDNEY, of Granville, Langley Park Road, Sutton, in the county of Surrey, England, a subject of the King of Great Britain, have invented certain new and useful Improvements in Turbines, of which the following is a specification.

This invention relates to turbines of the type in which the rotor comprises a drum and a band spiraled around the periphery of the drum to form a continuous duct of several convolutions and one of the purposes of the invention is to increase the efficiency of the rotor by forming said band to present a multitudinous succession of baffles or frictional resistances to the flow of the motive fluid which is circulated through the duct by either suction or pressure.

20 A further purpose of the invention is to provide the rotor with inlet and outlet chambers communicating with the ends of the duct and formed in a novel manner between cooperating members of the band and drum structure so as to revolve therewith.

25 A further purpose of the invention is to provide a novel interlocking connection between the drum and engaging portions of the band whereby the latter is securely keyed to the drum independently of the screws or other fastening means usually employed for holding the band in position.

30 A still further purpose of the invention is to design the rotor for use either with or without an outer casing, certain parts of the rotor employed to form a chamber communicating with the outer end of the duct when the rotor is unenclosed, being omitted when an outer casing is provided so as to leave the outer end of the duct open to the interior of the casing.

35 Other purposes and advantages of the invention, not specifically stated above, will become apparent from the following detailed description and accompanying drawings, in which—

40 Fig. 1 is a vertical longitudinal sectional view through one-half of a rotor constructed in accordance with my invention.

45 Fig. 2 is a view similar to Fig. 1 but showing a modification of the invention.

Fig. 3 is a fragmentary vertical transverse section on the line 3—3 of Fig. 1.

50 Fig. 4 is a view similar to Fig. 3 but taken along the line 4—4 of Fig. 2.

55 Fig. 5 is a fragmentary, vertical, trans-

verse, sectional view of a further modification of the invention showing the rotor as constructed for enclosure in an outer casing.

Fig. 6 is a detailed sectional view taken along the line 6—6 of Fig. 1 showing the interlocking connection between the band and the drum structure; and

Fig. 7 is a sectional detailed view of a modified form of band.

Referring more particularly to the drawings, 5 represents a drum equipped with end flanges 6 and 7 and an intermediate flange 8 and having the peripheral portion thereof cut away or recessed to form a channel 9 extending between the flanges 6 and 7 and through the intermediate flange 8, the latter being slotted for this purpose as indicated at 10.

In the form of invention illustrated in Figs. 1 and 3, the inner sides of the end flanges and both sides of the intermediate flange are stepped to provide a series of bearing faces 11 separated by risers 12 which are graduated to increase in radial depth from the periphery of the drum to the outer perimeter of the flanges. These bearing surfaces 11 are utilized, as shown, to support and separate the several convolutions of the spirally wound bands 13, which are of the gradually widening type and have their inner ends fastened to the periphery of the drum in spaced relation to a radial wall 14 of the channel 9 so that the said channel forms an inlet chamber or port which is closed at the outer side by the convolutions of the bands 13 and at the ends by the flanges 6 and 7. The flange 6 is apertured for the connection of an inlet pipe 15 through which fluid is admitted to the channel 9 to pass outwardly through the duct 16 formed between the convolutions of each band.

In this connection, it will be noted that the band is corrugated or cross channeled on both sides in such manner as to provide a series of baffles 17 along opposite sides of the duct 16 whereby increased frictional resistance is offered to the flow of the motive fluid.

As shown to advantage in Fig. 6 the marginal portions of the bands 13 resting on the bearing faces 11 are keyed to the latter by a tongue and groove connection 18, suitable packing 19 being interposed between the bands and bearing faces to prevent leakage therebetween. In addition to this interfitting connection the bands are further

held to the bearing faces by means of screws 20.

As the type of rotor disclosed in Figs. 1 and 3 is intended to be used without an outer casing, the bands 13 are enclosed within annular cover plates 21 having the marginal edges thereof suitably secured to the end and intermediate flanges of the drum. A packing strip 22 is interposed between the bands and the cover 21 in spaced relation to the outer terminals 23 of the bands so as to provide an intervening outlet chamber 24 extending between the flanges 6 and 7 and through the intermediate flange 8 by reason of a slot 25 formed in the latter for this purpose. The flange 6 is provided with an outlet opening to which is connected an outlet conduit 26 through which the fluid passes from the chamber 24. The inlet and outlet pipes 15 and 26, respectively are carried from the flange 6 through the shaft 27 on which the drum 5 is mounted.

In the operation of the turbine the fluid passes through the pipe 15 to the inner chamber or channel 9 and from thence through the ducts 16 of the several bands to the outer chamber 22 and outlet pipe 26 and it will be noted in this connection that the duct 16 gradually increases in radial depth from the inner to the outer end as the result of the aforementioned graduation of the risers 12 intervening between the several convolutions of the band.

In the modification disclosed in Fig. 2, the stepped bearing faces 11 are eliminated and the bands made of uniform width throughout, the necessary clearance between the convolutions of each band to provide the duct 16 being obtained by providing the band with raised or thickened margins 28. In this form of invention, the duct 16 is sealed or closed at the sides by welding or otherwise cementing the convolutions of the bands together at the thickened marginal portions 28. The keying of this type of band to the drum is effected by providing the inner sides of the flanges 6 and 7 and both sides of the intermediate flange 8 with radially disposed ribs 29 fitting in radial recesses 30 formed in the marginal portions of the band. By suitably graduating the raised margins 28 employed in this form of invention, the clearance space or duct 16 formed between the convolutions of the band is gradually increased in radial depth from the inner to the outer end, as shown in Fig. 4.

In the further modifications shown in Fig. 5, the cover plates 21 and packing strip 22 of the preceding figures is omitted, so as to leave the outer end of the duct 16 open to the interior of a stationary outer casing 31 in which the rotor is enclosed. In this form of invention, the chamber formed between the rotor and the casing 31 may be

subjected to either pressure or mechanically actuated suction and the motive fluid withdrawn or admitted by way of the pipe 15 previously described, in which case natural wind pressure conducted by a pipe from a cowl or the like may be employed.

It will also be apparent, that in the construction disclosed in Fig. 1 the pipe 15 may be used either as the inlet or outlet pipe, depending on whether it is desired to circulate the motive fluid toward or away from the drum 5 and the said circulation may be effected in any desired manner by either pressure or suction.

The bands 13 are preferably formed in one continuous length, but, if desired, may be made up of several sections joined by a tongue and groove connection, as disclosed in Fig. 7, suitable packing being interposed between the meeting edges of the sections as indicated at 32.

As many changes could be made in the above construction and many widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

1. A turbine comprising a drum, a band spiraled around the drum to form a continuous duct of several convolutions, means closing the duct at the sides, an inlet chamber formed conjointly by the band and drum structure at the inner end of the duct, an outlet chamber formed conjointly by the band and drum structure at the outer end of the duct and inlet and outlet conduits connected with said chambers.

2. A turbine comprising a drum provided with a transverse peripheral recess, a band spiraled around the drum to form a continuous duct of several convolutions, the inner end of the band being secured to the periphery of the drum in spaced relation to a wall of said recess so as to provide an intervening chamber closed at the outer side by the convolutions of the band, flanges carried by the drum engaging the margins of the band and serving to close the ends of said chamber, a fluid conduit connected with said chamber to supply motive fluid thereto and spacing means interposed between the convolutions of the band serving to gradually increase the radial depth of the duct from the inner to the outer end.

3. A turbine comprising a drum, a band spiraled around the drum to form a continuous duct of several convolutions having an inlet at its inner end, flanges carried by the drum and engaging the sides of the band, a cover positioned between said flanges and enclosing the band and a packing strip inter-

posed between the cover and the band in spaced relation to the outer terminal of the band to form an outlet chamber communicating with the outer end of said duct and an outlet conduit connected with said chamber.

4. A turbine comprising a drum equipped with spaced flanges, a band spiraled around the drum between said flanges to form a continuous duct of several convolutions having an inlet at the inner end and outlet at the outer end, said flanges and engaging portions of the band being formed with interfitting projections serving to key the band to the drum to prevent creeping of the band.
- 10 5. A turbine comprising a drum equipped with spaced flanges having the inner sides

formed to provide stepped bearing surfaces, a band of gradually increasing width spiraled around the drum with the several convolutions of the band resting upon and secured to said bearing surfaces, the marginal portions of the band and the engaging bearing surfaces being provided with interfitting projections serving to key the band to the drum to prevent creeping of the band. 20 25

In witness whereof I have hereunto set my hand in the presence of two witnesses.

WILLIAM JOHN EDNEY.
